UNITED STATES PATENT OFFICE

BENJAMIN DOWICK, OF JERSEY CITY, NEW JERSEY

HAIR RETAINER

Application filed January 6, 1932. Serial No. 535,056.

This invention relates to devices for hair retention, and particularly for retaining the hair of women's and children's bobbed heads. Its principal object is to provide a simplified, 5 inexpensive, conveniently manufacturable, light, durable, and efficient device which can be worn in concealed state and wherewith the wearer's hair and particularly the side locks will be retained in desired or appropriate 10 manner.

Other objects and advantages will herein-after appear.

In the accompanying drawings—

Fig. 1 is a perspective view illustrating 15 the manner in which the device of this invention is worn and how it operates to properly retain the hair in required condition.

Fig. 2 is a plan view of the device.

Fig. 3 is a similar view showing a modifica- 20 tion of the device.

Fig. 4 is a side elevation of the device shown in Fig. 3.

The hair retaining device 1 comprises a 25 wire band 2 of metal or any other suitable substance, which band may be semicircular, crescent shaped, or otherwise formed so as to fit to the rear portion of the head of the wearer. The band 2 is made springy, to cause the forward or end portions 3 thereof to em- 30 brace the sides of the head with light and re-silient pressure. At each terminal 4 of the band the material thereof is looped outwardly and rearwardly to form an elongated eye 5, and the material is bent over and along 35 the convex side 6 of the arcuate band to con- stitute a hair holding and grasping means 40 terminating in a corrugated portion 7 which bears resiliently against the exterior of the band for hair retention.

When wearing this device, the user places 45 the same against the head, underneath the hair, in completely concealed state, as shown, and the user may then insert the side locks 50 into the retaining devices 5, 7 which will thereby hold the locks in retarded requisite position, as illustrated in Fig. 1. The re-tained side locks in turn hold back the entire 55 bulk of bobbed hair in the desired appropri- ate condition. It will be evident that particu- 60 lar charm is imparted to the wearer's bobbed

head by the use of this efficient device, be-cause of the fact that the device itself is com-pletely concealed, and only its highly im-proved effect, which enhances the wearer's 55 good appearance, can be seen.

According to the modification shown in 60 Figs. 3, 4, the band 2 is made of flat mate-rial, and its exterior retaining devices 8 pro-vide large loops 9 with large eyes 10 and its rearward clamping portions 11 follow the 65 contour of the convex side of the band, with-out utilizing the corrugated forms shown in Fig. 2. This device is deemed more adaptable for utilization where the wearer's bobbed hair is unusually thick or coarse.

Variations may be resorted to within the 65 scope of the invention.

Having thus described my invention, I 70 claim:

1. A hair retainer comprising the combi- 75 nation of a member adapted to concealingly locate against the rear of the wearer's head and underneath the wearer's hair, and each end of said member having a hair retaining device located on the exterior side thereof and adapted to engage the side locks of the 80 wearer.

2. A hair retainer comprising the combi- 85 nation of a member adapted to concealingly locate against the rear of the wearer's head and underneath the wearer's hair, and each end of said member being bent rearwardly and against the exterior thereof and being adapted to engage the side locks of the 90 wearer.

3. A hair retainer comprising the combi- 95 nation of a member adapted to concealingly locate against the rear of the wearer's head and underneath the wearer's hair, and each end of said member being springy and bent rearwardly upon the exterior side thereof for engaging the side locks of the wearer.

4. A hair retainer comprising the combi- 100 nation of a curved band adapted to concealingly locate against the rear of the wearer's head and underneath the wearer's hair, said band being springy to bear resiliently against the wearer's head, and each end of said band having a hair retaining device located on the

convex side thereof and adapted to engage the side locks of the wearer.

5. A hair retainer comprising the combination of a curved band adapted to concealingly locate against the rear of the wearer's head and underneath the wearer's hair, and each end of said band being bent rearwardly and against the exterior convex side thereof and being adapted to engage the side locks of the wearer.

6. A hair retainer comprising the combination of a curved band adapted to concealingly locate against the rear of the wearer's head and underneath the wearer's hair, said band being springy to bear resiliently against the wearer's head, and each end of said band being bent rearwardly and against the exterior convex side thereof and being adapted to engage the side locks of the wearer.

20 7. A hair retainer comprising the combination of a member adapted to concealingly locate against the rear of the wearer's head and underneath the wearer's hair, and each end of said member having a hair retaining 25 device adapted to engage the side locks of the wearer.

Signed at the city of New York, in the county of New York, and State of New York, this 7th day of December, A. D. 1931.
